Atty:

UNITED STATES PATENT OFFICE.

WILLIAM SANDERS, OF ST. LOUIS, MISSOURI, ASSIGNOR TO THE ONE MINUTE CHURN COMPANY, OF SAME PLACE.

DESIGN FOR A CHURN-FRAME.

SPECIFICATION forming part of Design No. 25,584, dated June 2, 1896.

Application filed April 27, 1896. Serial No. 539,320. Term of patent 14 years.

To all whom it may concern:

Be it known that I, WILLIAM SANDERS, of the city of St. Louis, State of Missouri, have invented a new and original Design for 5 Churn-Frames, of which the following is a full, clear, and exact description, reference being had to the accompanying drawing, forming a part hereof.

In the drawing the figure is a side elevation of a churn-frame embodying my design.

The essential feature of my design consists in a body having an arm projecting from one end thereof and at right angles thereto, a second arm projecting from said body at a 10 point near the first arm and parallel with said first arm, a third arm projecting from the opposite end of said body from said first arm and parallel therewith, the last-mentioned arm being somewhat longer than the first two 15 mentioned arms, a fourth arm projecting at right angles from near the free end of said third arm, a fifth arm projecting at right angles from the free end of said fourth arm and parallel with said third arm, a circular lug 20 attached to the free end of said first-mentioned arm and in alinement with the end of said second arm, three circular lugs attached to said body in alinement with each other and on the side opposite from said arms and circular lugs in alinement with each other and 25 attached to the free ends of said third and fifth arms, said body and all of said arms being approximately T-shaped in cross-section.

The body consists of the straight portion 30 1, curved portion 2, the straight portion 3, and the straight portion 4, having the enlarged single flange 5, all of said parts being joined together and substantially T-shaped in cross-sections. The arm 6 is attached to 35 the free end of the part 4 and projects at right angles thereto from the face of the alined flanges, or the face opposite the single flange 5. To the free end of said arm 6 is attached the circular lug 7, and said arm 6 extends across the end of said part 4, the 40 alined flanges of the part 4 intersecting the alined flanges of the said arm.

The arm 8 is positioned parallel with the arm 6 and with the face of its alined flanges

flanges of said arms 16, 17, and 18. A similar opening is formed between the arms 6 and 8 and bounded by the alined flanges of the arm 6, the part 4, and the arm 8.

5 I claim—

The design for a churn-frame, as herein shown and described.

toward the face of the alined flanges of the arm 6. The arm 8 passes across the opposite end of the part 4 from the end to which the arm 6 is attached, and thus the alined flanges of the part 4 and arm 8 appear to cross each other. The end of the part 3 intersects the single flange 9 of the arm 8, and the circular lug 10 is attached to the part 3 adjacent its junction with the arm 8 but on the opposite side of the said part from said arm 8. Bracing-ribs 11 extend from said circular lug to 55 the back side of the alined flanges of the part 1.

The curved part 2 is attached to the end of the part 3 opposite the lug 10, and the straight part 1 is attached to the opposite end of the curved part 2. The circular lug 12 is attached to the single flange or straight part 1, and bracing-ribs 13 extend from said lug 12 to the alined flanges of the curved part 2. A circular lug 14 is attached to the end of the part 1 opposite the lug 12, said lugs 10, 12, and 14 being in alinement with each other.

Bracing-ribs 15 extend from said lug 14 to the alined flanges of the part 1. The arm 16 is attached to the face of the alined flanges 75 of the part 1 and on the opposite side of said part from the lug 14, and said arm 16 extends at right angles from said part 1 in a line parallel with the arms 6 and 8. The single flange of said arm 16 intersects the face of the alined flanges of the part 1.

The circular lug 17^a is attached to the free end of the arm 16 and projects slightly therefrom in a line parallel with the single flange of said arm. The arm 17 projects at right angles from the arm 16 at a point near its free end, the single flange of said arm 17 projecting toward the lug 14. The arm 18 projects from the free end of said arm 17 and at right angles thereto and in a line parallel 90 with the arm 16, the face of the alined flanges of said arm 18 being toward the face of the alined flanges of the arm 16.

A circular lug 19 is fixed to the end of the arm 18 in alinement with the lug 17^a. A 95 square or rectangular opening is formed between the free end of the arm 16 and the arm 18, bounded by the faces of the alined

25. 584

In testimony whereof I affix my signature in presence of two witnesses.

WILLIAM SANDERS.
